(57) CLAIM

The ornamental design for a handheld massager, as shown and described.

DESCRIPTION

FIG. 1 is a bottom perspective view of the handheld massager, showing our new design;

FIG. 2 is a bottom view thereof;

FIG. 3 is a top view thereof;

FIG. 4 is a front view thereof;

FIG. 5 is a rear view thereof;

FIG. 6 is a left side view thereof; and,

FIG. 7 is a right side view thereof.

The broken lines in the drawings are for the purpose of illustrating portions of the handheld massager that form no part of the claimed design.
